INSTRUMENT CASE FOR A POROSIMETER

Joel D. Ducommun, Chavannes, Switzerland, assignor to
Baumgartner Papiers S.A.

Filed July 25, 1974, Ser. No. 491,924

Claims priority, application Switzerland Feb. 1, 1974

Term of patent 14 years

Int. Cl. D10—04

U.S. Cl. D10—46

FIG. 1

FIG. 2

FIG. 3

FIG. 4

FIG. 1 is a top, right, front perspective view of an instrument case for a porosimeter showing my new design;

FIG. 2 is a front elevational view thereof, the rear side, not shown, being plain and unornamented;

FIG. 3 is a right side elevational view thereof, the left side being a mirror image thereto;

FIG. 4 is a bottom plan view thereof.

I claim:

The ornamental design of an instrument case for a porosimeter, substantially as shown and described.
